UNITED STATES PATENT OFFICE.

ANDREAS OLSEN, OF EPHRAIM, UTAH.

HEARSE.

1,179,027.

Specification of Letters Patent.

Patented Apr. 11, 1916.

Application filed April 28, 1914. Serial No. 834,933.

To all whom it may concern:

Be it known that I, ANDREAS OLSEN, a citizen of the United States, and resident of Ephraim, in the county of Sanpete and 5 State of Utah, have invented a new and useful Improvement in Hearses, of which the following is a specification.

My invention relates to an improvement in hearses, with the object in view of providing a hearse that will be economical in 10 the manufacture, and one that will be substantial and attractive in appearance.

A further object is to provide a hearse body in which the artistic effect is incorporated in the construction, thereby doing away with such embellishments as draperies, 15 curtains and hangings, which occupy so much room within the hearse and collect dust and dirt, and also make it more sanitary.

A still further object is to provide a hearse body which will afford an unobstructed interior.

A practical embodiment of my invention 25 is represented in the accompanying drawings, in which—

Figure 1 represents a perspective view of my improved hearse body, Fig. 2 represents a transverse central section in two 30 planes taken through a column and pilaster on one side and the window and frame on the other, and Fig. 3 represents a detail horizontal section illustrating the manner of assembling the side walls.

The body of the hearse comprises a truck 35 2 formed by bearers 3, which are spaced apart and held by deck beams 4, which are notched at 5 to rest upon the bearers 3. A fascia 6 is secured to the bearer 3 to cover 40 the ends of the beams and form a neat finish. A deck 7 is located upon the deck beams 4. A molding 8 is secured to the fascia 6 beneath the deck 7, and a molding 9 is fixed to the bottom of the fascia, both 45 of which moldings form an attractive finish.

A series of columns 10 are mounted upon the deck 7 to support a frame 11. A bolt 12 passes through the frame 11, column 10, deck 7, deck beam 4 and bearer 3, and is 50 adapted to receive a nut 13, by which bolt and nut, the aforesaid parts are all locked together. A cornice 14 and roof 15 are secured to the frame 11 by bolts 16.

Ornamental sides 17 are slid between 55 lower channels 18 secured to the deck 7 by screws 18* and upper channels 19 secured

to the frame 11 by screws 20. These sides are made up by assembling pilasters 21 and window frames 22 in which may be placed decorative glass 23 or what is known as art 60 glass. To obtain a perfect joint between the pilasters 21 and window frames 22, I provide the abutting edges thereof with tongues 24 and grooves 25. I also cover the joints formed by the pilasters and frames 65 within the body of the hearse with a half round bead or strip 26. Thus it will be seen that by this construction I am enabled to obtain a very clear, unobstructed 70 space within the body of the hearse, and, at the same time, present a very attractive design without sacrificing the space within.

In Fig. 1 I have shown in perspective a body of a hearse as applied to a horse-drawn vehicle, but I do not wish to limit 75 myself to this particular form of body alone, as I may apply the body to a motor truck.

While I have shown the window frames of a design known as "cathedral effect," it 80 will be understood that I may make these windows of any other fanciful design without departing from the spirit and scope of my invention.

What I claim is:—

1. A hearse body comprising a truck, a deck thereon, a frame, columns interposed between said deck and frame, bolts passing through and locking the aforesaid elements together, side walls located between said 90 frame and deck adjacent the columns, and a roof secured to said frame.

2. A hearse body comprising a truck, a deck thereon, a frame, columns interposed between said deck and frame, bolts passing 95 through and locking the aforesaid elements together, side walls located between said frame and deck adjacent the columns, means mounted on the deck and frame for holding said side walls, and a roof secured to said 100 frame.

3. A hearse body comprising a truck, a deck thereon, a frame, columns interposed between said deck and frame, bolts passing through and locking the aforesaid elements 105 together, side walls located between said frame and deck adjacent the columns, means mounted on the under side of the frame and the upper side of the deck adapted to receive the side walls, and a roof secured to 110 said frame.

4. A hearse body comprising a truck, a

deck thereon, a frame, columns interposed between said deck and frame, bolts passing through and locking the aforesaid elements together, side walls located between said frame and deck adjacent the columns, channels secured to the frame and deck, and adapted to receive said side walls, and a roof secured to said frame.

In testimony, that I claim the foregoing as my invention, I have signed my name in presence of two witnesses, this April 21, 1914.

ANDREAS OLSEN.
